UNITED STATES PATENT OFFICE.

GEORGE R. EATON, OF OAK PARK, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE SYSTEM.

Application filed February 19, 1921. Serial No. 446,241.

To all whom it may concern:

Be it known that I, GEORGE R. EATON, a citizen of the United States of America, and a resident of Oak Park, county of Cook, and State of Illinois, have invented certain new and useful Improvements in Telephone Systems, of which the following is a specification.

My invention relates to telephone systems and has to do more particularly with a reverting busy test, by which the operator receives a distinctive busy signal when a test is being made at a jack multiply connected with a jack in which the answering plug has been inserted, and an object of my invention is the provision of an improved and simplified circuit arrangement which is positive in its operation.

My invention is illustrated in connection with an operator's cord circuit which is arranged for automatically cutting in the operator's telephone set on the cord conductors when an answering plug is inserted into a jack of the calling line and for automatically disconnecting said operator's telephone set from the cord conductors when the connection is completed by the insertion of a calling plug into the multiple jack of a called line.

My invention is also applicable for use in connection with cord circuits which are arranged for manually connecting the operator's telephone set with the cord conductors by the actuation of a listening key, and it is to be understood that I do not wish to be limited to the specific circuit arrangement as shown, as I intend using the test circuit of my invention in connection with other cord circuits.

For a more complete understanding of my invention, reference may be had to the accompanying drawings, in which—

Fig. 1 illustrates the reverting busy test circuit of my invention used in connection with a two-conductor cord circuit provided with automatic listening; and

Fig. 2 illustrates the reverting test circuit of my invention used in connection with a three-conductor cord circuit provided with automatic listening.

Referring now more in detail to Fig. 1, I show a party-line PL which has connected to it substations A and B. The line terminates at the exchange in a line circuit L comprising a line relay LR, cut-off relay CO,

line signal S and the multiple jacks J and J'. The cord circuit C comprises an answering plug AP and a calling plug CP, the two cords being connected by the heavily marked talking conductors with condensers K and K' interposed. The answering end of the cord circuit has an answering tip supervisory relay AT and an answering sleeve supervisory relay AS, the two relays controlling answering supervisory lamp AL. The answering sleeve supervisory relay AS energizes when the answering plug AP is inserted into a jack J of the calling line to connect the operator's set O to the cord conductors. The calling end of the cord circuit C has a calling tip supervisory relay CT and a calling sleeve supervisory relay CS, the two relays CT and CS controlling calling supervisory lamp CL. The calling sleeve supervisory relay CS actuates when the calling plug CP is inserted into the jack J' of the wanted line, and upon energization automatically disconnects the operator's set O from the cord conductors. A ringing key RK is also provided, which when actuated connects the ringing generator G for signaling the called substation.

To the right of the drawing I illustrate substation D, similar to that illustrated at substations A and B, said substation D being connected at the exchange in a line circuit L' similar to the line circuit L. The reverting tone test circuit TT comprises a polarized relay PR which is common to an operator's position and comprises a high resistance winding H and a low resistance winding LO and an armature AM. The winding H is energized whenever an operator tests the multiple jack of a busy line and attracts the armature AM to close a contact in the circuit of the low resistance winding LO through its alternate contact. The low resistance winding LO is operatively effective only when a multiple jack of the same calling line is tested. The coils H and LO of the polarized relay PR are wound so as to oppose each other for purposes as will be more fully hereinafter described.

When a party calls for another party on the same line and the operator tests in the usual manner by placing the tip of the calling plug to the sleeve of the multiple jack of the wanted line, the winding H of the polarized relay PR is energized and attracts its armature AM, which closes its

- contact to energize the low winding LO, which closes a shunt about the winding H, and consequently the armature AM retracts and opens the circuit of the winding LO. 5 When the polarized relay PR is in this condition an energizing circuit is again established for the winding H, which attracts the armature AM and again closes a circuit for the winding LO, and the winding LO in 10 turn places a shunt about the winding H. Due to this a vibratory circuit is established through the windings H and LO, and the vibration of the armature AM produces a regular vibratory tone which is transmitted 15 to the operator's head receiver, notifying her that the called substation that is wanted is on the same line as that of the calling subscriber. When a busy line other than the calling line is tested, although the winding 20 H is energized to close a circuit through the winding LO, the winding LO is not effective to shunt H and the operator receives the usual busy click only, notifying her of the busy condition of the line, all of which will 25 be more fully hereinafter described.

Assuming now that a subscriber at the substation A wishes to converse with another subscriber, say at the substation B on the same party line, the subscriber at A removes 30 his receiver from the switchhook, causing the energization of the line relay LR. It attracts its armature to light the line signal S. The operator, in response inserts an answering plug AP into the jack J, closing 35 an energizing circuit including the answering sleeve supervisory relay AS of the cord circuit C and the cut-off relay CO of the line circuit, from battery through the winding of AS, sleeve contact of the connected 40 plug AP and jack J, to ground through the winding of the cut-off relay CO. The latter operates and opens the circuit of LR, which de-energizes and effaces line signal S. The answering tip supervisory relay AT of 45 the cord circuit C also operates from ground through the relay AT, tip contacts of the plug AP and jack J, through the substation A and back through the sleeve contacts of the jack and plug and through the winding 50 of relay AS to battery. The relay AT upon energizing opens its normal contact 50 to prevent the answering supervisory signal AL from lighting. The closing of alternate contacts 10 and 11 of the answering sleeve 55 supervisory relay AS connects the operator's telephone set O to the cord conductors, and the operator now inquires the want of the calling subscriber. Having received the 60 number, she tests the multiple jack of the called line to determine its idle or busy condition, perhaps not knowing that the called subscriber B is located on the same party line with the calling subscriber A. In testing she places the tip of the calling plug CP 65 against the sleeve of the multiple jack j of

the wanted substation B in the usual manner. The sleeve of the jack J is at a battery potential above ground and a circuit extends from battery through the winding of the answering sleeve supervisory relay AS, 70 through the sleeve contacts of the connected plug AP and jack J, over conductor 12 to the sleeve contact 13 of the multiple jack j of the called line B. When the tip of the plug CP is placed against this sleeve 13, an energizing circuit is established for the high resistance winding H of the polarized relay PR of the test circuit TT, traced from battery at the sleeve 13 of the jack j, through tip contact 14 of the calling plug CP, normal contact 15 of the ringing key RK, normal contact 16 of the calling sleeve supervisory relay CS, conductor 17, to ground through the winding H of the polarized relay PR. The winding H, upon energization, attracts the armature AM of the polarized relay against the spring tension of the coil spring 18² suitably fastened to the armature AM to close the contact 18 of said relay PR, and the closure of this contact establishes an energizing circuit for the low resistance winding LO of the polarized relay PR, traced from ground through said low resistance winding, alternate contact 18, armature AM, conductors 19 and 20, contact 21, conductor 22, contact 23, through the winding of the relay AS to battery and ground. The circuit just traced through the low resistance winding LO shunts the winding H when the tip 14 of the plug CP touches the sleeve 13 of the multiple jack j of the wanted line, because both winding H and winding LO are then conductively connected to the winding of relay AS and so to battery. As the windings H and LO are wound to oppose each other, the winding LO upon energization tends to repel the armature AM which was attracted upon the energization of winding H. The shunt circuit about the winding H, as already described, decreases the current flow through the said winding H and the opposed winding LO overcomes the attractive force of the winding H, and due to the attractive force of the winding LO and the pulling effect of the spring 18² the armature AM retracts to open the alternate contact 18. A stop 19² is provided on the relay PR for limiting the pivotal movement of the armature AM when the armature is moved to open contact 18. The opening of alternate contact 18 interrupts the energizing circuit through the low winding LO, and upon the opening of alternate contact 18 of the relay PR the shunt is removed from about the winding H and the winding H again attracts the armature AM, and upon the closure of alternate contact 18 an energizing circuit through the low-wound winding LO is again closed. As long as the tip of the

- plug CP remains in contact with the sleeve of the jack J a vibratory circuit for the windings H and LO of the polarized relay PR thus exists, causing the armature AM to vibrate, which produces a special buzzing tone transmitted to the operator's head receiver, indicating to her that she has tested a multiple jack of the calling line. The special tone may be traced from potential at 5 the vibrating armature AM, over conductors 19 and 20 through the operator's head receiver to ground through AT, and this tone is also transmitted to the calling subscriber from the vibrating armature over conductors 19 and 20, alternate contact 11 of relay AS, conductor 21, normal contact 22, conductor 23, sleeve contacts of the jack J and plug AP and through the receiver at the 10 substation A and back to ground through the winding of relay AT. The operator may then notify the calling subscriber at the substation A to replace his receiver upon its switchhook so that she may ring the called-for subscriber B, and she will then 15 insert the calling plug CP into the jack of the said line, which in this case would be the jack J. She then removes answering plug AP. The relay CS is energized, closing the circuit for the calling supervisory lamp CL. 20 The operator will then signal the called-for subscriber on the party line by actuating the ringing key RK to connect ringing generator G to operate the bell at the called substation. Upon both subscribers removing 25 their receivers, they are ready for conversation. Upon replacing their receivers the usual disconnect signal is given and the operator withdraws the plug. 30 Assuming now that the subscriber at the substation A wishes to converse with a subscriber at the substation D, the operation of this circuit is the same as previously described, and relay CO of the line circuit L and the relays AT and AS of the cord circuit O operate as before described. The 35 operator's telephone set O is automatically connected to the cord conductors so that the operator may ascertain the want of the calling subscriber at the substation A, and having assumed that it is the substation D that is wanted, the operator now tests the multiple jack J' of the called line as to its idle or busy condition. If the line is busy there 40 will be a battery potential upon the sleeve of the multiple jack J' from another cord circuit connected thereto, and assuming that the line is busy, the placing of the tip of the plug CP against the sleeve of the jack J' of the wanted line establishes an energizing 45 circuit for the winding H of the polarized relay PR of the tone circuit TT, as before described, from battery to the sleeve of the jack J' to ground, through the winding of the high resistance winding H, and the said winding H upon energization attracts the 50 armature AM. The closing of alternate contact 18 of the relay PR, upon the attraction of the armature AM, closes an energizing circuit for the low resistance winding LO of the polarized relay PR, from ground 55 through the winding LO to battery and ground, through the answering sleeve supervisory relay AS, over the path previously described. Thus, the winding H of the polarized relay PR energizes whenever a 60 busy line is tested, and the winding LO is also energized when a busy line is tested, but there is no shunt placed about the winding H of the relay PR when the operator tests the multiple jack J' of a called line, 65 which is a line other than a calling line, because in the present instance, although winding LO gets its current through relay AS of its own cord as before, the relay H now gets its current through a relay AS (or CS, 70 as the case may be) of some other cord circuit than the one to which it belongs. The windings H and LO oppose each other as before, but the winding H holds the armature AM attracted in this case because it is not 75 shunted as just explained. Each time the operator tests jack J' she gets a single click test if the line is busy, and no click if it is 80 idle. 85 If idle, the operator inserts the calling plug CP into the multiple jack J', closing an energizing circuit of the calling sleeve supervisory relay CS and the cut-off relay CO' of the line circuit L'. The relay CS opens its normal contacts 22 and 51, disconnecting the operator's set O from the cord conductors. The opening of normal contact 16 of the relay CS cuts off winding H, and the closing of its alternate contact 52 completes the continuity of the tip conductor of 90 the cord. The operator then actuates the ringing key RK, connecting ringing generator G to the tip side of the line to ring the called-for subscriber. The ringing current circuit being traced as follows: from ground 95 through the generator G, alternate contact 15 of the ringing key RK, tip contacts of the plug CP and jack J', upper alternate contact of the cut off relay CO', through the call bell at the substation D, the lower alternate contact of relay CO', sleeve contacts of the jack J' and plug CP, alternate contact 15' of ringing key RK, through the resistance r to ground at g. The calling supervisory signal CL is lighted through alternate contact 52 to ground and remains in its lighted condition until the called-for subscriber answers, which answering brings about the energization of the calling tip supervisory relay, which opens the circuit 105 of the calling supervisory signal CL. 110 Upon the termination of conversation the subscribers at the substations A and D replace their receivers upon their respective switchhooks, which acts cause the de-energi- 120 125 130

zation of the answering tip supervisory relay AT and the calling tip supervisory relay CT to close circuits for lamp AL and lamp CL. The operator now withdraws the 5 answering plug AP and the calling plug CP from their respective jacks J and J', which brings about the de-energization of the relays CO and CO' and of relays AS and CS of the cord circuit, which brings about the 10 effacement of the supervisory signals AL and CL.

Referring now to Fig. 2, I illustrate my invention adapted for use in connection with a three-wire cord circuit, and to the left of 15 the drawing I show a party line comprising subscribers A' and B', the said party line terminating at the exchange in a line circuit L², comprising the usual cut-off relay CO², line relay LR², supervisory signal S², multiple jacks J² and J'. The three-wire cord circuit C' comprises an answering plug AP' and a calling plug CP', the two plugs being connected by the heavily marked talking conductors. The answering end of the cord 25 circuit C' comprises an answering sleeve relay AS' and a supervisory relay SR, the two relays controlling the answering supervisory lamp AL'. The calling end of the cord circuit C' comprises the calling sleeve relay CS' and the supervisory relay SR', the two 30 relays controlling the calling supervisory signal CL'. A ringing key RK' is also shown, which when actuated connects the ringing generator G' of the called line to 35 transmit ringing current to actuate the call bell thereat. The answering sleeve relay AS' is energized when the answering plug AP' is inserted into the jack of the calling line to connect the operator's set O' to the 40 cord conductors, and the calling sleeve relay CS' energizes when the calling plug CP' is inserted into the jack of the called line, which relay CS' upon energization automatically disconnects the operator's set O' 45 from the cord conductors.

To the right of the drawing I illustrate a 50 substation D' similar to that illustrated at the substations A' and B', the said substation D' terminating at the exchange in a line circuit L³ similar to L², said line circuit L³ comprising line relay LR³, cut-off relay CO³, line signal S³ and the multiple jacks J³.

The revertive tone test apparatus TT' associated with the cord circuit C' comprises 55 a polarized relay PR', having a high winding H' and a low winding LO' and an armature AM', and the operation of the test circuit TT' associated with the three-wire cord circuit as illustrated in this figure is similar to that of the revertive test circuit TT as illustrated in connection with Fig. 1.

Assuming that the subscriber A' initiates 60 a call, the removal of the receiver brings about the energization of the line relay LR² to light the line signal S². The

operator inserts an answering plug AP' into the jack J² of the calling line, bringing about an energization of the cut-off relay CO² and the answering sleeve relay AS', and also bringing about the energization of 70 the supervisory relay SR, which relay upon energization prevents the lighting of the answering supervisory lamp AL' at this time. The closing of alternate contacts 60, 61 and 62 of the relay AS' connects the 75 operator's set O' to the cord conductors, and the operator now inquires the want of the calling subscriber. Having received the 80 number of the called subscriber, she tests a multiple jack of the called line to determine its idle or busy condition. Assuming that it is the subscriber B' of the same party line that is wanted, the operator tests the multiple jack J' of the wanted line by placing the tip of the calling plug CP' 85 against the sleeve of the jack. The sleeve of the jack J' being at a battery potential above ground, which extends from battery through the winding of the answering sleeve relay AS', through the sleeve contacts of the connected plug AP' and jack J², over conductors 63 to the sleeve of the multiple jack J' of the line that is now being tested. When the tip of the plug CP' is placed against the sleeve of the jack J' an 90 energizing circuit is established for the high resistance winding H' of the polarized relay PR' of the test circuit TT', over a path traced from battery at the sleeve 64 of the jack J' through the tip 65 of the calling 100 plug CP', the normal contact 66 of the ringing key RK', conductor 67, through alternate contact 61 of the answering sleeve relay AS', the conductor 67', normal contact 68 of the sleeve relay CS', conductors 69 105 and 70, to ground through the high winding H' of the polarized relay PR'. The winding H' upon energization attracts the armature AM' against the tension of the coil spring 18' fastened to armature AM' to 110 close its alternate contact 18', and the closure of this contact 18' establishes an energizing circuit for the low resistance winding LO' of the polarized relay PR', traced from ground through the winding of the 115 said relay LO', alternate contact 18', the armature AM', conductor 71, normal contact 72 of the relay CS', conductors 73, through alternate contact 60 of the answering sleeve relay AS', to battery and ground 120 through the winding of the said relay AS'. A stop 19' is provided for limiting the pivotal movement of armature AM' in one direction.

The circuit just traced through the low resistance winding LO' shunts the battery flow that flows through the winding H' when the tip 65 of the plug CP' touches the sleeve 64 of the multiple jack J' of the wanted line, and the operation of the tone test circuit TT' 125

of Fig. 2 is the same as described in connection with Fig. 1 and transmits a reverting buzz tone to the head receiver in the operator's set O', notifying her that 5 she has tested a multiple jack which is connected with the jack in which the answering plug AP' is inserted. The operator on receiving this reverting tone notifies the calling subscriber at the substation A' to 10 place his receiver upon its switchhook so that she may ring the called-for substation B'. The operator will then insert the calling plug CP' into the jack J² of the said line, and the opening of normal contacts 72, 15 68 and 74 disconnects the operator's set O' from the cord conductors, and the subscriber at the substation B' will be signaled in the usual manner by the actuation of the ringing key RK', the operator having first 20 removed answering plug AP. The resistance RE associated with the operator's set O' is placed in circuit during the time that the operator's set O' is connected to the cord conductors, through alternate contact 25 62 of the relay AS' and the normal contact 74 of the relay CS', to balance the operator's circuit when the winding H is connected thereto, as already described. Upon the response of the subscriber the substa- 30 tions A' and B' are ready for conversation, and upon replacing their receivers the usual disconnect signal is given and the operator withdraws the plugs.

When the operator tests the multiple jack 35 of a called line other than the one in which the answering plug has been inserted, the operation of the tone test TT' is the same as described in connection with Fig. 1, and the operator receives the usual click in her 40 head receiver, notifying her of the busy condition of the wanted line, and a further description of the tone test circuit TT' is not thought necessary.

While I have illustrated my invention 45 operating in connection with a specific circuit arrangement, I do not wish to be limited to the same, as the reverting tone test of my invention is adapted for use in connection with other circuit arrangements and 50 changes and modifications may readily suggest themselves, but I aim to cover all such changes and modifications as come within the spirit and scope of the appended claims.

What I claim as new and desire to secure 55 by Letters Patent, is:

1. A telephone system including a calling line and a link circuit connected thereto at one end, and having at the other end a test terminal adapted to be applied to said line 60 to test it, and reverting test means including a high resistance relay winding energized on such application, a low resistance relay winding cut in responsive to such energization, to shunt and oppose said high winding, 65 to produce a characteristic busy tone.

2. A telephone system including a calling line and a link circuit connected by its one end to said line, and having at its other end a terminal adapted to be applied directly to a limb of said line to test it, and test 70 means including reverting test apparatus having a polarized relay for said circuit, said polarized relay having one of its windings energized when any busy line is tested to operate an armature contact a single 75 stroke, and another relay winding opposing said first winding effectively operated on a reverting test only to cause a vibratory movement of said armature contact.

3. A telephone system including a calling 80 line and a link circuit connected thereto at its one end, a terminal at the other end of the circuit having test means including reverting test apparatus comprising a polarized relay with an efficient winding energized when a busy line is tested, a relatively inefficient winding for said relay cut in by energization of the first winding, and shunting means for said second winding to render said second winding inefficient on a 90 reverting test only.

4. A telephone system including telephone 95 lines and a link circuit for interconnecting them having a terminal adapted to be applied to said lines to test them, a polarized relay for said terminal having a winding energized by current over said terminal wherever a test of a busy line is made, an opposing winding for said relay energized 100 by a contact closed responsive to the energization of the first winding, said opposing winding ineffective to overcome the initial energization of the first winding, and means including said opposing winding to drain current from the first winding on a 105 reverting test only.

5. In a multiple switchboard, a link circuit, an operator's telephone set for said link circuit, automatic means for connecting and disconnecting said operator's telephone set 110 and said link circuit, reverting test apparatus including a link circuit polarized relay energized directly by current from the test terminal of the circuit, to operate its armature a single stroke on each non-reverting test of a busy line, and means including a shunt about said relay for causing it to operate its armature a plurality of strokes at each test on a reverting call, said shunt 115 including a winding of one of the magnets of said relay.

6. In a telephone system, a party line and an operator's cord circuit having its answering plug connected to a jack of said line, a test relay having an energizing winding in circuit with the calling plug when used as a test plug, a circuit for energizing said winding on a reverting call, said circuit including a contact of the answering plug, and a short circuit about said answer- 120 125 130

ing plug contact closed by the energization of said winding to shunt and oppose said winding to render the same ineffective.

7. A telephone system comprising a telephone line, multiple jacks therefor, a link circuit provided with a revertive tone test relay having opposing windings and having its answering terminal connected to a multiple jack of said line, a circuit for energizing said tone test relay when the calling terminal of said circuit is applied to another multiple jack of said line, said circuit including a contact of the answering terminal and a switch contact operated by said relay to short-circuit said contact of said answering terminal.

8. A telephone system comprising telephone lines, multiple terminals therefor, a link circuit provided with a polarized revertive tone test relay having its answering terminal connected to one of said multiple terminals, means for energizing a winding of said relay when the calling terminal of said circuit is applied to the multiple terminal of any busy line, a contact closed on energization of said winding to cut in another winding of said relay opposing said first winding, and a connection thereon effective to shunt said first winding effective only when said calling terminal tests the line connected to said answering terminal.

9. A telephone system including telephone lines having multiple terminals, a link circuit for interconnecting said lines, a polarized revertive tone test relay, means for energizing the two windings of said relay in opposition when any busy line is tested, and means for energizing both of said windings in opposition and shunting one of them when the answering terminal of said link circuit is connected to one of said lines and the calling terminal of said circuit is used to test said line.

10. A telephone system including telephone lines having multiple terminals, a link circuit for interconnecting said lines having its answering terminal connected to one of them, an operator's telephone set, means responsive to the connection of the answering and calling terminals of said link circuit to said lines as calling and called lines to automatically connect and disconnect said operator's telephone set and said link circuit, a polarized test relay for the calling terminal having two windings, an armature

contact for said relay connected to a test receiving instrument, means for producing a steady energization of the windings of said relay when another and busy line is tested, and a circuit for the windings of said relay for producing a vibratory energization of said relay on a revertive test to give an indication to the operator, said circuit including a shunt about one of said windings of said relay.

11. A telephone system including telephone lines having multiple terminals, a polarized test relay having windings opposing each other when testing, circuit conditions effective on one condition of testing a busy line to cause one winding to prevail, and circuit conditions effective on another condition of testing a busy line to cause the other winding to prevail, said last condition including a shunt about the first winding.

12. A telephone system including telephone lines having multiple terminals, a link circuit connected at one end to a terminal of a calling line, a polarized test relay having one winding connected to the testing conductor of said cord circuit and having an armature contact actuated by said winding on testing another and busy line to connect its other winding to another conductor of said circuit, said windings being then in opposition and said first winding prevailing, a test receiving instrument sensitive to actuation of said relay, and test circuit connections conductively uniting said first winding to said other conductor only when a revertive test is made.

13. A telephone system comprising a calling telephone line, multiple jacks therefor, a cord circuit having an answering terminal and a calling terminal, an operator's telephone set, means for connecting said operator's telephone to said cord when said answering terminal is inserted into one of said jacks, a polarized relay having a high resistance coil and a low resistance coil, an armature for said relay connected to said operator's telephone set, circuits for said coils for operating the same to produce a single movement of said armature, and circuits for operating said coils to cause a vibratory movement of said armature.

Signed by me at Chicago, in the county of Cook and State of Illinois, this 17 day of February, 1921.

GEORGE R. EATON.
